UNITED STATES PATENT OFFICE.

JAMES V. THOMPSON, OF SPENCER, WEST VIRGINIA, ASSIGNOR OF ONE-FOURTH TO ISAAC MOORE, ONE-FOURTH TO HAMOND H. ROBEY, AND ONE-FOURTH TO FRED P. GOUGH, OF SPENCER, WEST VIRGINIA.

MAIL-BAG CATCHER AND DELIVERER.

No. 921,567.

Specification of Letters Patent.

Patented May 11, 1909.

Application filed August 1, 1908. Serial No. 446,399.

To all whom it may concern:

Be it known that I, JAMES V. THOMPSON, a citizen of the United States of America, residing at Spencer, in the county of Roane 5 and State of West Virginia, have invented new and useful Improvements in Mail-Bag Catchers and Deliverers, of which the following is a specification.

This invention relates to mail bag catchers 10 and deliverers, and one of the principal objects of the same is to provide a device for the purpose described which shall be simple in construction, which will work smoothly under all conditions and which is capable of 15 being folded to occupy but little space when not in use.

Another object of the invention is to provide a device of the character referred to which can be readily adjusted to deliver a 20 mail bag when the car is going in either direction and to catch or take up a mail bag hung from a crane at the station when the train is going in either direction.

These and other objects may be attained 25 by means of the construction illustrated in the accompanying drawings, in which,—

Figure 1 is a perspective view illustrating the entire device. Fig. 2 is a vertical section taken through the door frame to which the 30 mail bag delivering device is hinged. Fig. 3 is a vertical section taken at right angles to Fig. 2, and illustrating the mail bag delivering mechanism. Fig. 4 is a sectional view from front to rear looking downward upon 35 the mail bag supporting device. Fig. 5 is a vertical section of the delivering mechanism folded in compact form when not in use. Fig. 6 is a sectional view on the line 6—6 of Fig. 2, looking in the direction indicated by 40 the arrow. Fig. 7 is a detail sectional view of the sliding bolt detent. Fig. 8 is a detail section, showing the supporting hook on the crane, and illustrating the recess for the shank of the hook to permit adjustment in 45 supporting the bag when the train is going in either direction.

Referring to the drawing, the numeral 1 designates the side of a mail car, and in the opening in the side of the car is fitted a door 50 frame to which my mail bag deliverer is hinged. A crane for suspending a bag in position to be taken up by the moving train consists of a post or upright 2 having suitable braces 3, and at the top an arm 4 hinged at 5

and provided at its outer end with a hook 6, 55 said hook extending through the arm 4 and provided with a shank 7 fitting in a recess 8. The hook 6 is adapted to support a mail bag 9, and may be adjusted by turning the hook and disposing the shank 7 in the recess 8 oppositely to the position shown in Fig. 8. Connected to the inner end of the arm 4 is a wire loop 10, and attached to said loop is a connecting rod 11, the lower end of which is attached at 12 to a loop on a lever 13, said 60 lever being hinged to a staple 14 at its upper end and having its lower end engaged by a block 15 secured to the base of the crane. By disengaging the lower end of the lever 13 from the block 15, the arm 4 will fold against 65 the front side of the post 2, as will be understood.

The mail bag delivering mechanism comprises a frame 16 fitted into the side of the car. Connected to this frame upon opposite 75 sides are hinge members 17 comprising sockets having registering openings 18 therein to receive the hinge members 19 connected to the uprights 20 of the delivery frame. In order to swing the delivery frame from opposite sides of the door opening in the car I have provided a double sliding bolt 21 having 80 downwardly projecting fingers 22 which pass through the socket members 17 and the hinge members 19 to form a hinge at one side 85 or the other of the delivery frame. The bolt 21 is fitted to slide in a keeper 23 on the frame 16. A recess 24 in the bolt 21 is engaged by the keeper 23 to hold the bolt in an upper inoperative position. A handle 25 90 projects outward from the bolt to operate the same. It will be understood that there is a bolt 21 on opposite sides of the delivery frame and that one of said bolts is thrown into inoperative position to permit the door 95 to swing from that side.

The top 26 of the deliverer is provided with a recess 27 having curved walls 28, and pivoted at the inner end of said recess 27 is a catch 29 engaged by a pivoted latch 30 to which 100 a spring 31 is connected, the opposite end of said spring being attached to a staple 32 on one of the uprights 20. A series of rods 33 are connected to the top 26 and extend down to a frame 34 connected at its opposite sides 105 to the uprights 20. The rods 33 form a cage for catching the mail bag 9 suspended from the crane. A horizontal partition 35 is se-

cured to the uprights 20 and is supported in a horizontal position by means of the slotted braces 36 provided with studs 37 which permit them to slide on the uprights 20. The 5 partition 35 is provided with a central recess 38 in which is secured a rack bar 39. Fitted to slide on the rack bar 39 is a curved abutment 40 provided with a shank 41 having a bolt 42 formed thereon, said bolt extending 10 outwardly into a slot 43 in the partition 35 and engaging a ring 44 on a mail bag 45. Formed on the abutment shank 41 is an inwardly projecting member 46 through which projects a detent 47 surrounded by a spring 15 48, said detent adapted to engage the teeth of the rack bar 39 as the abutment is pushed inward by the mail bag 9 and to prevent recoil of the bolt 42.

The mail bag 45 is supported by the bolt 20 42 and rests upon an inclined delivery rack 49 comprising the side bars 50, the top cross bar 51 and a series of spaced rods 52 connected to the cross bar 51 at their upper ends, while their lower ends are attached to a cross 25 rod 53, the opposite ends of which extend through the bars 50 and are pivoted in the frame bars 20. Connected to the cross bar 51 is an eye bolt 54, and hinged to the eye bolt is a latch 55 provided with oppositely 30 projecting fingers adapted to engage a notch 56 in the partition 35, as shown more clearly in Fig. 3.

The operation of my invention may be 35 briefly described as follows:—When it is desired to deliver the mail bag 45 and to catch the mail bag 9, the bag 45 is suspended by the ring 44 from the bolt 42, while the bag 9 is suspended from the hook 6 on the crane. As the train moves toward the left in Fig. 1, 40 the ring on the mail bag 9 is carried into the slot 27 and comes into contact with the pivoted catch 29 which releases the latch 30 and swings the arm a across the slot 27 to confine the mail bag in the smaller portion of said

slot. The lower end of the mail bag 9 strikes 45 the abutment 40 and slides the bolt 42 out of the ring 44 of the mail bag 45 and permits said bag to slide out of the frame 49 into a receiving net at the side of the track. When the delivering mechanism is not required for 50 use, the parts may be folded into the position shown in Fig. 5 to occupy but little space.

From the foregoing it will be obvious that my invention is of comparatively simple construction, will work smoothly and efficiently 55 for its purpose and cannot readily get out of order.

I claim:—

1. A mail bag deliverer comprising a frame, hinge members extending from said frame, a car door frame provided with socket members for said hinge members, sliding bolts provided with fingers for engaging said socket members and hinge members upon opposite sides of said frame. 60

2. A mail bag deliverer comprising a frame, the top of said frame being provided with a recess to catch a mail bag, and a spring latch for holding the bag in the recess. 65

3. A mail bag deliverer comprising a 70 frame having a top provided with means for catching a mail bag, a partition in the frame provided with a sliding abutment, a bolt formed on said abutment for supporting a mail bag to be delivered, and an inclined 75 frame for holding the mail bag.

4. A mail bag deliverer comprising means for catching a bag, a frame for supporting the bag, a bolt, an abutment connected to said bolt, and a rack bar and detent for preventing the recoil of said bolt. 80

In testimony whereof I affix my signature in presence of two witnesses.

JAMES V. THOMPSON.
